CLAIM

The ornamental design for display screen portion with animated graphical user interface, as shown and described.

DESCRIPTION

FIG. 1 is a front view of a first image in a sequence for a display screen portion with animated graphical user interface according to a first embodiment of the new design;

FIG. 2 is a second image thereof;

FIG. 3 is a third image thereof;

FIG. 4 is a fourth image thereof;

FIG. 5 is a front view of a first image in a sequence for a display screen portion with animated graphical user interface according to a second embodiment of the new design;

FIG. 6 is a second image thereof;

FIG. 7 is a third image thereof; and,

FIG. 8 is a fourth image thereof.

Hatching depicts a contrast in appearance.

In the first embodiment, the appearance of the transitional image sequentially transitions between the images shown in FIGS. 1-4. In the second embodiment, the appearance of the transitional image sequentially transitions between the images shown in FIGS. 5-8. The process or period in which one image transitions to another image forms no part of the claimed design.

In the figures, the outermost broken line showing the display screen, and all other broken lines showing portions of the graphical user interface, illustrates portions of the article and forms no part of the claimed design. The outermost broken line defines the bounds of the claimed design and form no part thereof.
